US00D523403S

(12) **United States Design Patent** (10) Patent No.: **US D523,403 S**
(45) Date of Patent: **** Jun. 20, 2006**

(54) **SUBSTRATE FOR A SEMICONDUCTOR DEVICE**

(75) Inventor: **Yukiko Mizukoshi**, Kita-ku (JP)

(73) Assignee: **Kabushiki Kaisha Toshiba** (JP)

(**) Term: **14 Years**

(21) Appl. No.: **29/217,556**

(22) Filed: **Nov. 19, 2004**

(30) **Foreign Application Priority Data**

Sep. 9, 2004 (JP) 2004-027496

(51) LOC (8) Cl. **13-03**

(52) U.S. Cl. **D13/182**

(58) **Field of Classification Search** D13/182;

174/52.1, 255, 256; 257/676, 678, 691; 361/760

See application file for complete search history.

(57) **CLAIM**

The ornamental design for a substrate for a semiconductor device, as shown and described.

DESCRIPTION

FIG. 1 is a top plan view of a substrate for a semiconductor device, showing my new design; the opposite side being a mirror image thereof;

FIG. 2 is a front elevational view thereof;

FIG. 3 is a right side elevational view thereof; the opposite side being a mirror image thereof; and,

FIG. 4 is a rear elevational view thereof.
